United States Patent

Des. 238,773

Patented Feb. 10, 1976

238,773

BUMPER FOR TRUCKS

Ted L. Cline, Rush Springs, Okla., assignor to
Cline Industries

Filed Oct. 25, 1974, Ser. No. 517,873

Term of patent 14 years

Int. Cl. D12—16

U.S. Cl. D12—169

FIG. 1 is a front elevation view of a bumper for trucks incorporating my new design.

FIG. 2 is a top plan view thereof.

FIG. 3 is a rear elevation view thereof.

FIG. 4 is a bottom plan view thereof.

FIG. 5 is an end elevation view thereof.

FIG. 6 is a sectional view thereof taken along line 6—6 of FIG. 2.

FIG. 7 is an end elevation view thereof.

I claim:

The ornamental design for a bumper for trucks, as shown.
